VALVE OPERATING MECHANISM

Kenneth R. Nisbet, Washington, D. C.

Application November 4, 1932, Serial No. 641,263

9 Claims. (Cl. 123—90)

This invention relates to new and useful improvements in operating mechanism for valves of the tappet type and is especially designed for use in internal combustion engines, although not necessarily restricted in its use.

The types of valve actuating mechanism now in common use for tappet valves include a spring operatively connected to the stem of the valve for seating the head of the valve, a tappet or push rod operatively associated with one end of the valve stem or with an end of an additional rod or rods operatively connected to the valve stem, and a rotating cam, eccentric, or the like, for actuating the tappet or push rod. In this type of mechanism, it is essential that a gap or clearance be maintained between certain of the cooperating elements to permit expansion due to dissipation of heat through the mechanism. In valve mechanisms of the above referred to conventional types, this clearance is usually provided between the adjacent ends of the tappet and the valve stem or associated rod. To maintain a proper clearance at this point, the tappet is usually provided with some form of adjustment by means of which the overall length of the tappet may be varied. This adjustment usually consists of a stud threaded into the end of the tappet and maintained in adjusted position by means of lock nuts.

With the valve operating mechanism of the above mentioned types, wear occurs at at least two different points; namely, at the point of contact between the tappet and the actuating cam or eccentric and the point of contact between the tappet and the valve stem or operating rod. The clearance provided between the adjacent ends of the tappet and the valve stem, or operating rod, due to wear or improper adjustment at the above mentioned points, not infrequently varies or increases with the result that a tapping noise is produced every time the tappet and valve stem ends contact. It not infrequently is a difficult proposition to locate the valve actuating mechanism causing the disturbing noise in view of the fact that either or both of these contacting ends may have one or more flat surfaces or regions which are not truly right angularly arranged with respect to the axis of the tappet and valve stem. Due to frequent periods of partial rotation of the valve stem and tappet, these flat regions will be moved into and out of positions which will cause the above referred to tapping noise to start and stop at irregular intervals. Excessive or insufficient clearance caused by the above mentioned wear or faulty adjustment also will result in a decrease in the efficiency of the engine.

It is a fundamental object of this invention to provide a valve operating mechanism which will allow for necessary expansion due to dissipation of heat, eliminate tappet noises, reduce wear between the valve stem and tappet, and assist in maintaining greater engine efficiency throughout the life of the engine.

A further object of the invention is to provide a valve and tappet organization which may be assembled or disassembled with a minimum expense of effort and time.

A still further object of the invention is to provide a valve actuating mechanism which is exceedingly simple in construction and one which may be manufactured at a very nominal cost.

Other advantages and objects of the invention will be apparent during the course of the following description:

Figure 1 is a detail view, partly in section and partly in elevation, of a portion of the mechanism shown in Figure 2 but viewed at right angles thereto.

Figure 2 is a sectional view of one form of valve actuating mechanism embodying this invention.

Figure 3 is a plan view of a blank from which one of the elements disclosed in Figs. 1 and 2 may be formed.

Figure 4 discloses detail views of the connector element which is made from the blank shown in Fig. 3, and

Figure 5 is a detail longitudinal sectional view of a modified form of the invention.

In the drawing, wherein for the purpose of illustration is shown a preferred embodiment of the invention, the numeral 6 designates in its entirety the portion of an engine block or head which has the inlet and exhaust valves operatively associated therewith. This engine part 6 is formed with a valve seat 7 against which the head 8 of the valve engages to control the flow of fuel or burned gases through the passageway 9. The valve head 8 is provided with a stem 10 which passes through a valve guide 11 carried by the engine portion 6. The valve stem 10 has associated therewith, in any conventional manner, a spring 12 which functions to urge the valve head 8 toward the seat 7. The lower end of the stem 10 is formed with an annular groove 13 and this grooved extremity of the valve is operatively associated with the tappet or push rod 14. The upper end or extremity of this push rod also is provided with an annular groove which bears the reference character 15. The grooves 13 and 15 are shown with square edges, but may be beveled or round as desired. The push rod 14

is provided at its lower end with an enlargement 16 which is positioned in operative relation with respect to a cam element 17 carried by the cam shaft 18.

5 In Fig. 3 there is disclosed a blank 19 which is cut away, or bifurcated at its opposite ends 20 to form the spaced, parallel fingers 21. The inner edge of each of these fingers 21 is provided with an offset portion 22. These offset portions do not 10 extend the full lengths of the fingers but form portions raised with respect to the planes of the fingers. The blank constructed in a manner illustrated in Fig. 3 is intended to be formed of elastic material, such as spring steel, and to be 15 bent into U shape, as illustrated in Fig. 4. Figs. 1 and 2 illustrate the adjacent ends of the valve stem 10 and tappet 14 as having one of these U shaped spring connector units associated therewith by inserting the fingers 21 into the annular 20 grooves 13 and 15. It will be noted that these fingers straddle the valve stem and tappet when thus positioned thereby permitting the tappet to rotate on its vertical axis when the design is such that this is essential or necessary. The offset or raised portion 22 formed in the fingers 21 will provide seats to receive the adjacent portions 25 of the valve stem and tappet to prevent unintentional removal of the connector unit from its intended position. Due to the resiliency or elasticity of the connector unit 19 the adjacent, opposed ends of the valve stem 10 and tappet 14 are maintained constantly in contact with each 30 other.

When the valve mechanism shown in Figs. 1 35 and 2 is associated with an engine, the overall length of the mechanism should be such that a clearance will be provided between the inactive portion 17a of the cam 17 and the enlargement 16 of the tappet 14 when this inactive portion 17a 40 of the cam is opposite the said enlargement. This gap or clearance 23 will allow for necessary expansion in the mechanism due to dissipation of heat therethrough.

Figure 5 discloses a modification of the structure shown in Figs. 1 to 4, inclusive. In this modification, the valve stem 10a is provided with a transversely extending hole 13a and the adjacent end of the tappet 14a is provided with a transverse hole 15a. A spring connector unit 19a 50 is positioned with the offset portions 22a of its arms 21a positioned within the holes 13a and 15a. The wire connector element preferably is provided with one or more coils 24 which will function to constantly urge the arms 21a toward each 55 other.

It will be noted from the above description of this valve mechanism that no gap or clearance is provided between the adjacent ends of the valve stem 10 and the tappet 14. In view of this 60 fact no wear can occur at this point and it is very apparent that the ends of these members will not be rapidly moved into and out of contact with each other and no tapping noise can possibly be produced. With the necessary gap or 65 clearance provided at the point 23, or between the enlarged end 16 of the tappet and the periphery of the cam 17. There will be no engagement between the cam and tappet while the inactive portion 17a of the cam is opposite the tappet end 70 16. Engagement of the cam with the tappet will only occur while the active portion of the same is functioning to raise the tappet for actuating the valve. It will be apparent, therefore, that wear at this point in the mechanism materially 75 will be reduced. The cam shafts of internal com-

bustion engines of conventional design are usually located in the crank case of the engine with the tappet projecting through a wall of the case. The associated surfaces of the cam 17 and the enlarged end 16 of the tappet 14 therefore will be 5 constantly supplied with a film of oil from the crank case. This oil film will function to materially reduce wear at this point in the mechanism and will assist in preventing the development of any noise at the time of contact. 10

While my invention has been disclosed in connection with a valve mechanism suitable for an L or T head type of engine, it is to be understood that the invention may be as readily employed in connection with valve-in-head engines. When 15 the invention is used in a valve-in-head engine, it may be necessary to use either of two types of spring connectors at more than one point in the mechanism.

It is to be understood that the forms of this 20 invention herewith shown and described are to be taken as preferred examples of the same, and that various changes in the shape, size, and arrangement of parts may be resorted to without departing from the spirit of the invention 25 or the scope of the subjoined claims.

Having thus described the invention, I claim:

1. Engine valve mechanism comprising a valve, a seat for the valve, means for urging the valve towards its seat, a valve lifting rod, a rotatable 30 actuating element, and means for connecting the valve and its actuating rod to prevent separation of the same whereby the clearance left for expansion will occur between the actuating rod and the rotatable actuating element, said means comprising a substantially U-shaped spring member having its arms directly and detachably connected to said valve stem and lifting rod. 35

2. In combination, a valve having a stem provided with a groove adjacent its end, a valve push rod coaxial with the stem provided with a groove adjacent its end, a cam for lifting the push rod and valve, and means for connecting the adjacent grooved ends of the push rod and valve stem to prevent separation of said ends, comprising a 40 substantially U-shaped spring member having portions engaged in said grooves.

3. In combination, a valve having a stem, a valve push rod coaxial with the stem, a cam for lifting the push rod and valve, and a substantially 50 U-shaped spring connector element having its arms directly connected to the valve stem and push rod to prevent separation of the same.

4. In a valve operating mechanism, a connector for directly connecting and maintaining the valve 55 stem and push rod of said valve operating mechanism constantly in contact with each other comprising a substantially U-shaped spring member.

5. In a valve operating mechanism, a connector for maintaining the valve stem and push rod 60 of said valve operating mechanism constantly in contact with each other comprising a substantially U-shaped spring member having its arms formed with oppositely offset portions 65 adapted to engage a valve stem and push rod to prevent unintentional removal of said spring member.

6. In a valve operating mechanism, a connector for maintaining the valve stem and push rod 70 of said valve operating mechanism constantly in contact with each other comprising a substantially U-shaped spring member having its arms bifurcated.

7. In a valve operating mechanism, a connector for maintaining the valve stem and push 75 rod of said valve operating mechanism constantly in contact with each other comprising a substantially U-shaped spring member having its arms bifurcated.

rod of said valve operating mechanism constantly in contact with each other comprising a substantially U-shaped spring member having its arms bifurcated and offset portions formed in the inner sides of said furcations.

8. In a valve operating mechanism, a connector for maintaining the valve stem and push rod of said valve operating mechanism constantly in contact with each other comprising a substantially U-shaped wire spring having a coil

intermediate its ends and an offset portion in each arm.

9. In combination, a valve having a stem, a valve push rod cooperative with said stem, means for actuating said push rod and valve, and a spring connector element directly connected to the valve stem and to the push rod to prevent separation of the same.

KENNETH R. NISBET.
